UNITED STATES PATENT OFFICE.

HARRY STILLSON HART, OF CHICAGO, ILLINOIS, ASSIGNOR TO THE RODGER BALLAST CAR COMPANY, OF CHICAGO, ILLINOIS, A CORPORATION OF ILLINOIS.

DUMP-CAR.

SPECIFICATION forming part of Letters Patent No. 743,278, dated November 3, 1903.

Application filed December 18, 1902. Serial No. 135,711. (No model.)

To all whom it may concern:

Be it known that I, HARRY STILLSON HART, a citizen of the United States, residing at Chicago, Illinois, have invented certain new and useful Improvements in Dump-Cars, of which the following is a specification.

This invention relates to that class of cars which are used for the purpose of carrying freight that may be dumped through the bottom portion thereof, and particularly to that class which have bottom portions for the dumping of the freight between the trucks and rails of the track, all of which will more fully hereinafter appear.

15 The principal object of this invention is to provide a simple, economical, and efficient dump-car—one that will carry the maximum load.

Further objects of the invention will appear from an examination of the drawings and the following description and claims.

The invention consists principally in a dumping-car in which there are combined a supporting-framework having upwardly-extending side and end boards and a bottom portion formed in three parts, two parts immovably fixed in flat planes and located directly over the car-trucks at each end of the car, and a V-shaped dumping hopper portion 30 at the center and between the car-trucks only.

The invention consists, further and finally, in the combination, arrangements, and details thereof as set forth in the following description and claims.

35 In the accompanying drawings, Figure 1 is a longitudinal sectional elevation of a car constructed in accordance with these improvements, taken on line 1 of Fig. 2 looking in the direction of the arrow; Fig. 2, a plan view of the same looking at it from above; Fig. 3, an enlarged cross-sectional elevation taken on line 3 of Fig. 1 looking in the direction of the arrow, and Fig. 4 a similar view taken on line 4 of Fig. 1 looking in the direction of the arrow.

In the art to which this invention relates it is well known that it is highly desirable to have a car which is adapted to carry different kinds of freight that can be dumped 50 through the bottom portion and that some

kinds of such freight are heavier than others. As a consequence, it is desirable to have a car which has a maximum carrying capacity—one that will carry in bulk form all the load that it is necessary to carry in this type of car. 55

The principal object of this invention, therefore, is to provide a dump-car which will embody the above-noted as well as other advantages, all of which will more fully herein-after appear. 60

In illustrating and describing these improvements I have only shown and described that which I consider to be new, taken in connection with so much as is old as will properly disclose the invention to others and enable those skilled in the art to practice the same, leaving out of consideration other and well-known mechanisms which if set forth herein would only tend to confusion, prolixity, and ambiguity. 65

In constructing a car in accordance with these improvements a supporting-frame is provided formed of side sills *a*, intermediate sills *b*, center sills *c*, end sills *d*, and other well-known members, as shown in the drawings, but which, as they form no material part of the invention, need no further consideration. This supporting-framework is provided with upwardly-extending side boards *e* and end boards *f*, secured thereto and held 80 in operative position in any well-known and usual manner.

It is highly desirable to have the car so arranged that it may have all the capacity of a gondola car and the efficiency of a hopper-bottom dumping-car. In order to accomplish these results, a bottom portion is provided and formed in three parts—two relatively fixed or immovable parts *g*, laid in flat planes at the ordinary floor-level at each end of the car and directly over the car-trucks, and the third part formed in the shape of a V-shaped hopper *h*, arranged between the trucks only, with its apex *i* at or near the longitudinal center of the car. One of the inclined portions or walls of the hopper extends downward only to the bottom of the transverse sills and is provided with a dumping-door *j*, pivotally attached to such sills and adapted to be raised and lowered by means of the chain 95 100

k and rock-shaft *l*. The other inclined wall of the hopper extends downward from the perpendicular side wall of the car between the longitudinal bottom sills of the framework 5 and between and downward beyond the transverse sills to the apex or center of the hopper and is fixed and rigid throughout.

The flat bottom portions, as above suggested, extend entirely over the car-trucks *m* 10 and are relatively immovable or fixed to the car-frame, so that no material can be dumped onto the car-trucks. The inclined sides or walls which form the hopper-bottom extend upwardly and outwardly to a point considerably above the floor-level, where they meet 15 the side boards of the car.

The principal advantages incident to the use of a car constructed in accordance with these improvements are, first, a larger carrying capacity than usual is provided; second, the advantages of a dumping-car are obtained, and, third, the car can be loaded either over the trucks or between the same whenever necessary or desirable.

25 I claim—

1. In a car of the class described, the combination of a supporting-framework comprising longitudinal and transverse sills having permanent upwardly-extending side and end 30 boards, a bottom formed of flat portions over the car-trucks at each end and a relatively fixed *V*-shaped dumping hopper portion at the center and between the car-trucks with its apex arranged at or near the longitudinal 35 center of the car comprising two inclined side walls one of which extends downward between and beyond the longitudinal and transverse sills in fixed and rigid relation thereto, to the center and bottom of such hopper, and end 40 walls for such hopper extending upward to but not beyond the flat floor portions leaving the ends of the hopper open above the level of the flat portion of the floor, substantially as described.

45 2. In a car of the class described, the combination of a supporting-framework comprising longitudinal and transverse sills provided with permanent upwardly-extending side and end portions, a bottom portion formed of relatively immovable flat portions arranged over 50 the car-trucks and a relatively fixed or immovable *V*-shaped dumping hopper portion at the center extending between the trucks only with its apex arranged at or near the longitudinal center of the car comprising two 55 inclined side walls one of which extends downward between and beyond the longitudinal and transverse sills in fixed rigid relation thereto, to the center and bottom of such hopper, and end walls for such hopper extending upward to but not beyond the flat floor portions leaving the ends of the hopper open above the level of the flat portion of the floor, substantially as described.

60 65 3. In a car of the class described, the combination of a supporting-frame comprising longitudinal and transverse sills provided

with upwardly-extending side and end boards, a bottom portion formed in three parts, two flat portions relatively immovably fixed at each 70 end at or near the ordinary floor-level and extending entirely over the car-trucks, a *V*-shaped dumping hopper portion at the center between the car-trucks only and with its apex arranged at the longitudinal center of the car 75 comprising inclined side walls relatively fixed and extending above the floor-level to meet the side boards of the car, one of which side walls extends downward between and beyond the longitudinal and transverse sills to the 80 longitudinal center of the car and forms one side of the apex of the hopper, and end walls for such hopper extending upward to but not beyond the flat floor portions leaving the ends of the hopper open above the level of the flat 85 portion of the floor and a dumping-door in the opposite inclined hopper bottom portion extending downward into engagement with the lower edge of such rigid hopper-wall, and pivotally connected to the sills, substantially 90 as described.

4. In a car of the class described, the combination of a supporting-framework comprising side and end sills, a bottom comprising flat portions extending over the car-trucks 95 at each end, a hopper portion having inclined side walls extending upward beyond the flat portion of the floor, and having end walls extending upward to but not beyond such flat 100 floor portions leaving the ends of the hopper open above the level of the flat portions of the floor, and perpendicular side and end walls extending upward from the flat portion of the floor at the outer edges thereof, substantially 105 as described.

5. In a car of the class described, the combination of a supporting-framework comprising side and end sills, a bottom comprising flat end portions extending over and resting upon such sills, a hopper portion having inclined side walls extending upward beyond the flat portion of the floor, and having end walls extending upward to but not beyond such flat floor portions leaving the ends of the hopper open above the level of the flat 110 portions of the floor, and upright side and end walls extending upward from the flat portion of the floor at the outer edges thereof and above the upper edge of the inclined side 115 walls of the hopper portion, substantially as 120 described.

6. In a car of the class described, the combination of a supporting-framework comprising transverse and longitudinal sills, a bottom comprising flat end portions extending 125 over such transverse and longitudinal sills and resting thereon, a relatively fixed central hopper portion having inclined walls extending upward beyond the floor-level and downward between the longitudinal sills, and having end walls extending upward to but not beyond such flat floor portions leaving the ends of the hopper open above the level of the flat portions of the floor, and upright side 130

and end walls extending upward from the floor-level at the outer edges of the flat portions of the floor and above the upper edges of the side walls of such hopper portion, substantially as described.

7. In a car of the class described, the combination of a supporting-framework comprising transverse and longitudinal sills, a bottom comprising flat end portions extending over such transverse and longitudinal sills and supported thereby, a relatively fixed hopper portion having one inclined side wall extending upward beyond the floor-level and downward to the longitudinal center of the car and an opposite inclined wall extending upward beyond the floor-level and downward to the lower edge of the sills, and having end walls extending upward to but not beyond

such flat floor portions leaving the ends of the hopper open above the level of the flat portions of the floor, upright side and end walls extending upward from the floor-level at the outer edges thereof and above the upper edges of the inclined hopper-walls, a door pivotally mounted at the lower edge of one of the inclined hopper-walls and extending downward into engagement with the lower edge of the opposite inclined hopper-wall, and means for closing and holding such door in closed position and permitting it to be opened, substantially as described.
